FLOWER POT SUPPORT

Otto E. Belknap, La Habra, Calif.

Application October 29, 1956, Serial No. 43,560

Term of patent 14 years

(Cl. D35—3)

Fig. 1 is a perspective view of a flower pot support embodying my new design;

Fig. 2 is a top plan view of Fig. 1, rotated approximately 15° to the right;

Fig. 3 is a front elevational view of Fig. 2; and

Fig. 4 is a left side elevational view of Fig. 3.

I claim:

The ornamental design for a flower pot support, substantially as shown.
